NOVELTY PACKAGE

Stanley B. Stefan, Hamtramck, Mich., assignor
of fifty per cent to Jane H. Stefan, Hamtramck,
Mich.

Application June 29, 1945, Serial No. 602,339

3 Claims. (Cl. 46—151)

1

This invention relates to a novelty package in the form of a doll and has more specific reference to an article in this line of endeavor which is characterized by a candy-containing bag jacketed in an enclosing garb or costume, whereby to provide a unique and attractive candy-packaging and retailing doll.

Needless to say, and as the preceding introductory statement of the invention implies, I am sufficiently conversant with the general state of the art to which the invention relates to full well appreciate that candy boxes and equivalent food containers are externally dressed and ornamented in many and divers manners. What is more, it is admittedly not new to exteriorly decorate bags and other containers to represent dolls, and the like. It follows, therefore, that in carrying out the principles and innovations of the instant structure, I have evolved and produced what is believed to be a clever and ingenious adaptation of parts which harmoniously coact in permitting a pre-shaped candy-filled bag to serve as a "mannequin" or mount, so-called, for a predetermined costume, the components which make up the costume conforming to and coinciding with the predetermined companion portions of the candy-filled mannequin-forming bag.

More specifically, in carrying out my aims and ideas, I contemplate the provision of a novel costumed candy-filled bag functioning as a doll, the costume and the contents of the bag coinciding in bringing to the purchaser native costumes of different nationalities and calculated to appeal to the esthetic senses of discreet purchasers appreciative of factors of eye-appeal and educational suggestion, whereby to adapt same for favors and gifts for women and children.

Other objects, features and advantages of the invention will become more readily apparent from the following description and the accompanying illustrative drawings.

In the drawings, wherein like numerals are employed to designate like elements throughout the views:

Figure 1 is a perspective view of the candy-filled paper bag gathered and shaped to form a crude but original mannequin-like foundation for reception and display of the items which go to make up the complete garb or costume.

Figure 2 is an elevational view of a plug-like insert forming the head.

Figure 3 is a view in side perspective showing the mask or face mounted on the head, the latter in dotted lines.

2

Figure 4 is a perspective view of a head covering, such, for example, as a bonnet.

Figure 5 is a perspective view of the shirtwaist.

Figure 6 is a view of the skirt.

Figure 7 is a plan view of a handkerchief usable as a wrap-around scarf or shawl.

Figure 8 is a perspective view of an insert forming a stabilizing form for shaping purposes.

Figure 9 is a rear view of the doll nearly dressed.

Figure 10 is a perspective front view of the finished or completely dressed doll.

Referring now to the drawings by distinguishing reference numerals, attention comes first to

15 Figure 1, which shows the paper bag 11. This is of appropriate stock to promote longevity and to worthily serve its purposes. It is of suitable dimensions to provide capacity for, let us say, one pound of candy. It is preferably flat on

20 the bottom, at least flat when filled, as indicated at 12, so that it is susceptible of being set straight up on a display counter, or the like, in actual practice. It is gathered at points between its upper and lower ends, as indicated at 13, this by

25 a suitably fashioned and endless surrounding band 14. This therefore defines a lower body portion 15 of appropriate dimensions, and an upper bulbous-like bust or body portion 16. The open mouth of the bag is further gathered by

30 surrounding endless bands 17 to define an open neck 18. In practice, it is desired to have a form-defining insert 19 in the bag to prevent crushing and to facilitate maintaining the desired contour. This is brought out in Figure 8,

35 the same being a cardboard panel having upper and lower portions 16a and 15a, respectively, and a restricted waist portion 14a. The extension stub, denoted at 18a, protrudes upwardly through and beyond the gathered neck 18.

40 Referring to Figure 2, here we see the plug-like head 20. This is a ball of paper properly twisted and wrapped and with the lower end portion 21 of general conical form so as to permit it to be tucked down into the neck 18 in an obvious

45 fashion. It is sewed in place once it is properly lodged in the neck. Incidentally, the bands 14 and 17 can be rubber or of such stock as is available. It is to be noted, too, that the neck extension 18 protrudes to pilot the pendant 21 into place.

46 The false face is denoted at 22 in Figure 3. This may be of pre-formed paper, plastic or whatever is found suitable and practicable for the purposes. It is glued, or otherwise fastened on 55 the so-called head 20. The head covering, broad-

ly speaking, is here shown, in a specific form, as a bonnet 23. Then in Figure 5 I show a so-called shirtwaist 24 with a frilly collar 25 and appropriate waist band 26. The gathered and pleated skirt is denoted by the numeral 27 and is provided with appropriate ties 28. The numeral 29 designates an appropriately decorated handkerchief which functions as a shawl. The skirt 27 conforms to the part 15 of the candy-loaded bag, whereas the shirtwaist 24 conforms to the bust or upper body portion 16. The other parts fit in place in the sequence and manner illustrated in the drawings.

Although it is incidental, it is to be observed that the finished doll is both without arms and hands. Further, it is to be pointed out that the bag 11 is of suitable paper stock, the form 19 is of suitable weight and satisfactory cardboard or the like, and the articles which go to make up the complete ensemble or costume are of paper or equivalent stock, depending on the market conditions, price requirements, etc.

Obviously, the fundamental principles will be the same as far as the production of the novelty candy-bag doll is concerned, but I desire it understood that the external appearance and garb will vary according to traditions, national customs, and other commercial and educational purposes. For example, it is believed that the sale of dolls in this category will acquaint juvenile purchasers with the different types of costumes worn by various nationalities. At the same time, it is not thought necessary to dwell at length upon the commercial aspects, since I am interested in the innovation and primarily the idea of the pre-shaped candy-containing bag serving as a foundation or mannequin for a changeable ensemble, the latter in accordance with the dictates of the user.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

I claim:

1. A combination candy bag and paper doll of the class described comprising a paper bag adapted to be filled with candy, or the like, the central portion of said bag being gathered to define upper and lower body portions, the bottom being substantially flat, the mouth of the bag being open and also gathered and retained in

gathered state to form a neck, and an insert in said bag having a restricted central portion and upper and lower coating portions cooperating with the upper and lower body portions of the bag, the upper portion of said insert having an extension projecting upwardly through and beyond said neck.

2. A combination candy bag and paper doll of the class described comprising a paper bag adapted to be filled with candy, or the like, the central portion of said bag being gathered to define upper and lower body portions, the bottom being substantially flat, the mouth of the bag being open and also gathered and retained in gathered state to form a neck, and an insert in said bag having a restricted central portion and upper and lower coating portions cooperating with the upper and lower body portions of the bag, the upper portion of said insert having an extension projecting upwardly through and beyond said neck, a plug-like insert including a tapered lower end portion adapted for disposition and fastening in said neck, said portion forming an unadorned head.

3. A combination candy bag and paper doll of the class described comprising a paper bag adapted to be filled with candy, or the like, the central portions of said bag being gathered to define upper and lower body portions, the bottom being substantially flat, the mouth of the bag being open and also gathered and retained in gathered state to form a neck, an insert in said bag having a restricted central portion and upper and lower coating portions cooperating with the upper and lower body portions of the bag, the upper portion of said insert having an extension projecting upwardly through and beyond said neck, a plug-like insert including a tapered lower end portion adapted for disposition and fastening in said neck, said portion forming an unadorned head, and a mask for anchorage on said head.

STANLEY B. STEFAN.
